(57) **CLAIM**

The ornamental design for a multi-function exercising machine, as shown and described.

DESCRIPTION

FIG. 1 is a top perspective view of a multi-functional exercising machine, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof;

FIG. 8 is a bottom perspective view thereof;

FIG. 9 is a second top perspective view thereof, showing the exercising machine in condition of use;

FIG. 10 is third top perspective view thereof, showing the exercising machine in condition of use; and,

FIG. 11 is a forth top perspective view thereof, showing the exercising machine in condition of use.

The broken lines showing a human figure illustrates environmental structure which form no part of the claimed design.
